(No Model.)

J. J. DEAL.
PERMUTATION LOCK.

No. 512,506.

Patented Jan. 9, 1894.

UNITED STATES PATENT OFFICE.

JOSIAH J. DEAL, OF CANTON, ASSIGNOR TO THE DEAL LOCK COMPANY, OF AKRON, OHIO.

PERMUTATION-LOCK.

SPECIFICATION forming part of Letters Patent No. 512,506, dated January 9, 1894.

Application filed March 29, 1893. Serial No. 468,182. (No model.)

To all whom it may concern:

Be it known that I, JOSIAH J. DEAL, a citizen of the United States, and a resident of Canton, county of Stark, State of Ohio, have 5 invented a new and useful Improvement in Commutation-Locks, of which the following is a full, clear, and exact description, reference being had to the accompanying drawings, making part of this specification.

10 My invention relates to improvements in commutation locks, and consists of certain features of construction and combination of parts as will be hereinafter described and pointed out in the claims.

15 Figure 1, of the accompanying drawings is a view in perspective illustrating my invention as applied to a door lock. Fig. 2, is a longitudinal section of the same. Fig. 3, is a view of the face of one of the disks. Fig. 4, 20 is a perspective of one of the locking disks. Fig. 5, is a perspective of the lock as applied to a shackle for padlock. Fig. 6, is a longitudinal section of same, and Fig. 7, is a perspective showing the form of the locking and 25 spacing disks.

Referring to Fig. 2, A represents the knob bar or spindle on one end of which is provided a series of grooves numbered 1, 2, 3, 4, 5, 6, and a series of alternating collars, a, b, c, 30 d, e, f; at the end portion of the spindle is a pin h, projecting a distance from the sides as shown. B, represents the knob, and C a retaining plate. Between the knob and retaining plate is placed alternately a series of locking disks, j, k, l, m, n, o, p, and spacing disks q, and at the end portion next the knob a locking disk r in form substantially as that shown in Fig. 3, having side apertures u to receive the bolts t, and a central aperture v, 40 having side kerfs s' to secure the end of the spindle A and the projecting pins h. The locking disks R are of the form shown in Figs. 4 and 7, having a side aperture u, a central aperture v, that overreaches and cuts 45 into a side aperture w which is of less diameter, thus forming across the disk an elongated aperture of two intersecting circles or apertures of different diameters. At the side opposite the aperture u is an elongated aperture x, and at the same side an

outwardly projected finger portion y. The bolt t is passed through the aperture u, which serves as a pivot about which the locking disks R may be vibrated a distance to lock or release the parts as hereinafter described. 55

The parts are preferably assembled as shown in Figs. 1 and 2, that is, finger portions y, projecting from opposite sides to allow of more room for manipulation; the bolts t are passed through apertures u in the retaining plate and similar apertures in the spacing plates q, and the locking plate r, and turned into threaded apertures in the knob by which the parts are held in position. 60

To provide for a slight contraction or expansion of the bolts and disks, a groove is provided in the under side of the retaining disk C, and a spring z as shown in Fig. 7, is placed therein the energy of which is exerted against the disk next thereto. 65

The knob as shown in Fig. 2, is unlocked or loose and free to turn on the spindle A, without moving the latch bolt D of the door lock; the locking operating disks are placed to move transverse the spindle in opposite directions; referring to Fig. 2, it will be seen that the small part w, of the aperture embraces the small part of the spindle in the groove l, between the shoulder on the spindle and collar a. Disk k, occupies a similar position between the collars b, c, and disk m, a similar position between the collars f, and the locking plate r. Disk n, on the opposite side occupies a similar position, the small part w of the aperture embracing the small part of the spindle in the groove e, between the collar a, b, to prevent a longitudinal movement of the lock and knob on the spindle. It will also be noticed that the large part v of the aperture in the disks o, l, p, are in line with 70 collars on the spindle to allow the collars to pass through. 75

To lock the knob to the spindle, for the purpose of this application, I have shown the lock set on combination or disks j, k, n of the disks pivoted on the bolts t. Disks j and k, are moved to the right, and n to the left which movement will bring the large part v, of the aperture in the disk in register with o, l, p. The knob may now be drawn out a distance 80 85 90 95 100

on the spindle, the pins *h* passing into the kerf *s'*, thereby locking the knob to the spindle for the purpose of rotating it to move the lock bolt *D*. The disks may now be thrown in 5 confusion to remain so until it is desired to disengage the knob to lock the door. In other words the knob is unlocked from the spindle to lock the door lock.

To change the combination, the opposite 10 knob is removed, the spindle with the commutation lock removed from the door lock, and the bolts *t*, taken out, after which the locking disks *R* may be turned over to occupy the same position, but to swing in the opposite 15 direction, or they may be turned end for end and pivoted on the opposite bolt or may occupy another place in series; thus it will be seen that an almost indefinite number of combinations may be had. It will be understood 20 that the letter *R* designates the movable locking disks. The letters *j*, *k*, *l*, *m*, &c., are used to designate their position in the combination or commutation.

The spindle with the commutation lock attached 25 may be applied to any form of knob, latch lock, or the commutation parts may be applied to a padlock shackle as represented by the parts shown in Figs. 6 and 7.

Referring to Fig. 6, *E* represents a T shackle 30 having head portion *a'*, transverse the neck *a²*, and a shank *a³*, in which are provided grooves 1, 2, 3, 4, 5, 6, and collars *a*, *b*, *c*, *d*, *e*, *f*, as shown on the lock spindle *A*, Fig. 2. The locking disks *j*, *k*, *l*, *n*, *o*, *p*, and the spacing 35 disks *q*, and retaining disk *C*, are fac-similes of the parts shown in Fig. 2. A plate or disk *F*, is provided having threaded apertures to receive the ends of the bolts *t*, in place of the knob *B*. The smaller part *w*, of the aperture 40 in the movable or locking disks *j*, *k*, *n*, *o* embraces the smaller part of the shank and collars *a*, *b*, *c*, *d*. To prevent the removal of the bolts *t*, when the lock is in service, an apertured plate or disk *G* is placed over the heads 45 of the bolts and secured to the plate *C* by a small screw *H*, turned into a threaded aperture in the retaining disk *G*, the head portion of the screw to be under or partly under the shoulder of the shank. This lock is set on the com-

bination *j*, *k*, *n*, *o*. *j*, *k*, are turned to the right, 50 and *n*, *o*, to the left, to arrange the large part *v* of the aperture in the disks in line with the collars, so that the shank of the shackle may be drawn out of the lock.

The combinations given are of the simplest 55 to illustrate the working of the lock, but other and more complicated combinations would be adopted in practice.

Having thus fully described the object and 60 nature of my invention, what I claim, and desire to secure by Letters Patent, is—

1. The combination with a door lock spindle having a series of projecting portions of a series of spacing disks, a series of locking disks adapted for transverse vibration to carry said 65 disks between said projections to lock said parts against longitudinal movement on the spindle for the purpose set forth.

2. The combination with a door lock spindle having a series of depressions and projections of a series of locking disks adapted to vibrate transverse said spindle to release the parts and allow the knob to move longitudinally on said spindle, a locking disk *r* and pin *h*, whereby the knob is locked or engage 75 with the spindle for the purpose set forth.

3. The combination with a door lock spindle having a series of grooves and collars, of the spacing disks, the knob *B*, retaining disk *C*, bolts *t*, and disks *R*, adapted to vibrate 80 transverse the bolts to engage or disengage the spindle, substantially as described and for the purpose set forth.

4. The combination with a lock shackle having a head portion *a'*, transverse the neck *a²*, 85 a shank *a³*, having a series of alternating grooves and collars, of the spacing disks *q*, the locking disks *R*, and bolts *t*, about which the disks *R* may be vibrated transverse the shackle, substantially as described and for 90 the purpose set forth.

In testimony whereof I have hereunto set my hand this 25th day of March, A. D. 1893.

JOSIAH J. DEAL.
